COMBINED TAPE PRINTER AND DISPENSER

Melvin J. Larsen, Woodland Hills, Calif., assignor to
Reynolds Industries, Inc., Santa Monica, Calif., a cor-
poration of California

Application April 11, 1955, Serial No. 35,449

Term of patent 14 years

(Cl. D74—1)

Figure 1 is a perspective view of a combined tape printer and dispenser, showing my new design;

Figure 2 is a side elevational view thereof, taken in the direction of the arrow 2 in Figure 1;

Figure 3 is an end elevational view; and

Figure 4 is a top plan view.

I claim:

The ornamental design for a combined tape printer and dispenser, substantially as shown.
